UNITED STATES PATENT OFFICE.

MERRIL MABON, OF ROCHESTER, NEW YORK, ASSIGNOR TO HICKOK MANUFACTURING COMPANY, INC., OF ROCHESTER, NEW YORK, A CORPORATION OF NEW YORK.

DESIGN FOR A BELT BUCKLE.

Application filed September 23, 1926. Serial No. 19,155. Term of patent 3½ years.

To all whom it may concern:

Be it known that I, MERRIL MABON, a citizen of the United States, residing at Rochester, in the county of Monroe and State of New York, have invented a new, original, and ornamental Design for a Belt Buckle, of which the following is a specification, reference being had to the accompanying drawing, forming part thereof.

In the drawing:

Fig. 1 is an end edge view of the belt buckle showing my new design; and
Fig. 2 is a front face view thereof.

I claim:

The ornamental design for a belt buckle, as shown.

MERRIL MABON.
